UNITED STATES PATENT OFFICE.

JACOB ROTHLIS, OF MUNCIE, INDIANA, ASSIGNOR TO W. D. SMITH SILVER CO., OF CHICAGO, ILLINOIS, A CORPORATION OF DELAWARE.

DESIGN FOR A SPOON OR SIMILAR ARTICLE.

Application filed December 17, 1926. Serial No. 20,068. Term of patent 7 years.

To all whom it may concern:

Be it known that JACOB ROTHLIS, a citizen of the United States, and a resident of Muncie, in the county of Delaware and State of Indiana, has invented a certain new, original, and ornamental Design for Spoons or Similar Articles, of which the following is a specification, reference being had to the accompanying drawings, forming part hereof.

Fig. 1 is a front elevation of a spoon

illustrating the improved design, tines of a fork being indicated in dotted outline.

Fig. 2 is a rear elevation of the same.

Fig. 3 is a side elevation of the same.

Fig. 4 is a cross-sectional view taken through the handle along side 4—4 of Fig. 1.

What is claimed is:

The ornamental design for a spoon or similar article, as shown.

JACOB ROTHLIS.
